(21) Appl. No.: 29/273,626

(57) CLAIM

(22) Filed: Mar. 9, 2007

The ornamental design for a pair of trousers having a front label, as shown and described.

(51) LOC (9) Cl. 02-02

DESCRIPTION

(52) U.S. Cl. D2/742

FIG. 1 is a front perspective view of the invention;

(58) Field of Classification Search D2/742,

FIG. 2 is a front view of the invention;

D2/738, 857, 712; 2/22, 23, 79–80, 223,
2/227, 235–236, 247, 919

FIG. 3 is a back view of the invention;

See application file for complete search history.

FIG. 4 is a right side view of the invention;

(56) References Cited

FIG. 5 is a left side view of the invention;

U.S. PATENT DOCUMENTS

FIG. 6 is a top view of the invention; and,

3,959,826 A * 6/1976 Hakanson 2/227

FIG. 7 is a bottom view of the invention.

D466,676 S * 12/2002 Lyden D2/742

1 Claim, 7 Drawing Sheets
